Primary Examiner — Robin V Webster*Assistant Examiner* — Keith J Wilson(74) *Attorney, Agent, or Firm* — Morgan, Lewis & Bockius LLP(57) **CLAIM**

I claim the ornamental design for an off ground tent with sloped ceiling, as shown and described.

DESCRIPTION

FIG. 1 is a perspective view of my new design of an off-ground tent with sloped ceiling;

FIG. 2 is a front view of the design of FIG. 1;

FIG. 3 is a back view of the design of FIG. 1;

FIG. 4 is a left side view of the design of FIG. 1;

FIG. 5 is a right side view of the design of FIG. 1; and,
FIG. 6 is a top view of the design of FIG. 1.

The broken lines shown represent environment only and form no part of the claimed design.
